UNITED STATES PATENT OFFICE.

CLARK S. COMSTOCK, SR., OF EAST ORANGE, NEW JERSEY.

BUCKLE OR THE LIKE.

1,273,460.

Specification of Letters Patent. Patented July 23, 1918.

Application filed October 9, 1917. Serial No. 195,495.

To all whom it may concern:

Be it known that I, CLARK S. COMSTOCK, Sr., a citizen of the United States of America, residing in East Orange, in the county 5 of Essex and State of New Jersey, have invented certain new and useful Improvements in Buckles or the like, of which the following is a specification.

This invention relates to garment buckles or loops, and aims to provide certain improvements therein.

The buckles to which my invention relates are usually constructed of wire which is bent to form a lower button-receiving portion 15 more or less triangular in form, the two ends being brought inwardly and then upwardly, and sharpened to form the prongs of the buckle. The frame portion of the buckle is usually hinged to the loop near the 20 prongs. The button-receiving portion is provided with a button recess at its bottom and a constricted throat leading to such button recess. Such buckles are designed especially for overalls and other cheap garments, and are consequently made very 25 cheaply, in the fewest number of operations and of the least quantity of wire stock. The constricted throat leading to the button recess is designed to be of such dimensions 30 that it must be sprung apart slightly to admit the button shank, so that after the button is in its recess the contraction of the throat will be sufficient to hold the button in place. As a matter of practice, however, 35 these throats are seldom accurately made, and the same is true of the buttons they are designed to receive. Very slight deviations from the theoretical sizes are sufficient to produce such a loose fit that the contracted 40 throat will not hold the button in place. In such buckles there is practically little, if any, capacity for outward springing of the throat, so that such irregularities in the structure of the buckle and button cannot be 45 compensated for. Garment loops are also made in this same way, with the exception that instead of the ends of the wire being carried upwardly to form prongs, they are joined by a sleeve or the like, and the frame 50 of the buckle is accordingly omitted.

According to the present invention, I provide a construction in which very little more wire is used than in the common form, but I introduce sufficient springiness into the 55 structure to avoid any escape of the button, even though there are deviations from the

proper dimensions in the buckle or in the button shank. According to the invention, I omit the throat which leads to the button recess, and in lieu thereof introduce what 60 may be termed a "looped stop", against which the button impinges when it seeks to escape, and which looped stop has sufficient springiness to overcome any errors in the 65 proportions.

In the drawing, wherein I have illustrated several forms of the invention,—

Figure 1 is a plan of a buckle embodying the invention;

Fig. 2 is a section on the line 2—2 in 70 Fig. 1;

Fig. 3 is a plan of a loop constructed according to the present invention, and

Fig. 4 is a side elevation thereof.

Referring first to Figs. 1 and 2, let A indicate the buckle as a whole, which is formed with two wire members B and C. The portion B is preferably triangular in form, having a button-receiving portion B', and is bent at its middle to form a button recess 80 at its bottom, and the ends being carried upwardly to form prongs D and E. The portion C has a prong-rest F at its middle, and the ends thereof are bent downwardly to engage horizontal portions G and H of the 85 part B. In the usual form of prior constructions the wire is continued from the button recess I directly upward to join the portions G and H. According to the present invention, however, on one side of the structure 90 I introduce a looped stop-member J which overlies the button-receiving recess so as to make a restricted passage K through which the button shank must pass in order to reach the recess I. The looped stop-member J is 95 preferably formed by bending the wire inwardly just below the horizontal portion G, is shown at L, and then downward obliquely, as shown at M, and then upwardly substantially parallel to M, as shown at N; the wire 100 is then turned abruptly at P and continued downwardly to the button recess. This stop-member introduces considerable resilience into the structure, since it can bend about the portions L and P to a considerable extent. At the same time it overlies the button recess near the top to such an extent that the button shank must be introduced in an oblique direction to reach its recess. As the width of the space K is less than the 110 diameter of the button shank, there is little or no chance for the button to escape. When

there is a tendency to this, the button shank reaches the stop and further accidental movement in this direction is prevented.

In Figs. 3 and 4 the same construction is shown, with the exception that the horizontal portions G and H are continued toward each other, as shown at 'G' and 'H', and coupled together by a sleeve Q, or in any other suitable manner. Of course, in this case the buckle frame C is omitted.

While I have shown and described several forms of the invention, it will be understood that I do not wish to be limited thereto since various changes may be made therein without departing from the spirit of the invention.

What I claim is:

1. A fastener comprising a wire member having a button-receiving portion and a button recess leading thereto, and a looped stop-member extending partially over the top of the button recess and adapted to yield to permit the entrance of the button to such recess, said stop-member formed of the same piece of wire as the portion of the buckle to which it is connected, and being rigidly connected with the wire forming the button recess on the side on which the stop member is located.

2. A fastener comprising a wire member having a button-receiving portion and a button recess leading thereto, and a looped stop-

member extending partially over the top of the button recess and adapted to yield to permit the entrance of the button to such recess, said looped stop-member comprising an elongated portion formed by bending the wire obliquely downward and then upward, and thence downwardly toward the button recess.

3. A fastener comprising a wire member having a button-receiving portion and a button recess leading thereto, and a looped stop-member extending partially over the top of the button recess and adapted to yield to permit the entrance of the button to such recess, said looped stop-member being formed by forming the wire inwardly to form a portion L, downwardly to form a portion M, and upwardly to form a portion N, and thence downwardly toward the button recess.

4. A fastener comprising a wire member having a button-receiving portion and a button recess leading thereto, and a looped stop-member extending partially over the top of the button recess and adapted to yield to permit the entrance of the button to such recess, said stop-member being unconnected across its ends.

In witness whereof, I have hereunto signed my name.

CLARK S. COMSTOCK, SR.
